UNITED STATES PATENT OFFICE.

OSCAR J. SUNDSTRAND, OF ROCKFORD, ILLINOIS, ASSIGNOR, BY MESNE ASSIGNMENTS, TO SUNDSTRAND CORPORATION, OF WILMINGTON, DELAWARE, A CORPORATION OF DELAWARE.

ADDING AND RECORDING MACHINE.

Application filed June 16, 1924, Serial No. 720,187. Renewed November 5, 1928.

This invention relates to adding and recording machines of the type wherein two totalizers are provided to receive items of two different classes, as, for example, debits and credits. Such a machine may be used to list items of different classes in a single column or in separate columns.

The object of the invention, generally stated, is to provide a very simple and efficient machine of the type indicated.

A special object is to adapt a machine of the Sundstrand type to the registration and recording of items of two different classes.

In the accompanying drawings, Figure 1 is a fragmental longitudinal vertical sectional view of an adding and recording machine embodying the features of my invention. The machine is shown at rest, and in adjustment to accumulate items in the rear or debit totalizer. Fig. 2 is a view of the keyboard of the machine. Fig. 3 is a detail view of the means for preventing casual rotation of the pinions while out of mesh with the racks, both totalizers being shown out of mesh with the racks. Fig. 4 is a fragmental right-hand side view, the parts being shown in the same position as in Fig. 1. Fig. 5 is a fragmental end elevation looking from the right-hand side of Fig. 4. Fig. 6 is a detail view of the element 269. Fig. 7 is a detail view of the element 235. Fig. 8 is a fragmental right-hand side elevation. The total key 221 is shown depressed, the handle 27 is on its return stroke, and the pinions 25 have just been withdrawn from the racks. The part 257 has prevented the pawl 158 from engaging the pin 163. Fig. 9 is a detail view of the member 242. Fig. 10 is a view illustrating the means for raising and lowering the type bars, the parts being shown in the initial or rest position. Fig. 11 is a right-hand side view showing a portion of the means for obtaining totals, the parts being shown in the position assumed when there is no item set up in the machine, and the position assumed after a spacing stroke of the handle has been taken. Fig. 12 is a sectional detail view. Fig. 13 is a fragmental view illustrating the means for throwing the totalizers into and out of operation, the rear or debit totalizer being shown in operative relation to its actuating racks. It may be assumed in Fig. 13 that the racks

are about to descend to add a debit item. Fig. 14 is another view of the means for throwing the totalizers into and out of action, the forward or credit totalizer being shown in operative relation to its actuating racks in Fig. 14, the handle has started to return to initial position, and the racks are about to descend to add a credit item. Fig. 15 is a detail view of one of the plates by means of which the totalizers are movably supported. Fig. 16 is a detail view of the element 142. Fig. 17 is a detail view of the cam plate 190. Figs. 18 and 19 illustrate the action of the carrying mechanism. In Fig. 18, one of the debit racks 130 has been released so as to cause carrying from one order to the next higher. In Fig. 19, one of the credit racks 131 has been permitted to descend to effect carrying from one order to the next higher. Fig. 20 is a fragmental perspective view of one of the parts of the carrying mechanism. Fig. 21 is a horizontal sectional view of the totalizers and related parts in the position occupied during the forward stroke of the operating handle when accumulating and the return stroke of the handle during a clearing operation. Figs. 22, 23, 24 and 25 are facsimiles of work done on the machine.

Although the invention is herein shown as embodied in a machine of the ten-key type such as is disclosed in the Sundstrand Patent No. 1,198,487, certain features thereof are not limited to use in machines of that character.

The sheet or tape on which the items and totals are to be printed and the calculations recorded may be supported in any ordinary or suitable way. In the present instance, a cylindrical platen 2 is employed. In the machine herein shown, the printing is effected by means of vertically reciprocatory type bars 3, one such bar being provided for each numerical order. The machine herein illustrated is adapted to register and print up to 9,999,999.99, hence nine bars 3 are employed, as will be understood from Fig. 21. Said bars are arranged compactly side by side, and they are guided near their upper ends by means of a transverse bar 5 fixed in the framework of the machine, said bar extending through vertically elongated openings 6 in the type bars. The lower ends of the type

bars are located between and guided by two transverse fixed bars 7 and 8, the latter being slotted to receive the rear edges of the type bars.

- 5 Each type bar 3 is provided at its upper end with ten type 9 adapted to print from naught to nine, respectively. The uppermost type is adapted to print "0," the next to the top "1," and so on.
- 10 In the present machine the means for vertically moving each bar 3 into and out of printing position comprises an arm 10 carrying a headed stud that lies in an elongated opening 11 in the type bar. The arm 10 is loosely mounted on a shaft 12 which is supported in the framework of the machine. Rigid with the arm 10 is an arm 13 which is yieldingly connected through two helically coiled contractile springs 14 to a rod 15.
- 15 The latter is carried by two side members 16 (Fig. 1) which are guided for approximately vertical movement by a transverse rod 17 fixed in the framework of the machine, said rod extending through elongated openings 18 in the side members 16. Pivoted to the upper ends of the side members 16 are two levers 19 (Fig. 4) which are mounted in the framework of the machine to swing on the axis 19^a. To the lower ends of the levers 19 are pivoted links 23 (Figs. 1 and 4) the forward ends of which are pivoted to two crank arms 24 and 25 fixed to opposite ends of the main rock shaft 26. The shaft 26 is arranged to be rocked by means of a handle 27 or crank 27 mounted to swing upon the axis 28. The connection between the handle 27 and the arm 24 may be of any suitable character, as, for example, a link 27^a (Fig. 10) connected to a crank arm 27^b arranged to 35
- 30 swing with the handle. It will of course be understood that an electric motor may be used to rock the shaft 26, if desired.

When the operator pulls the handle 27 forward, the crank arms 24 and 25 swing upwardly, thereby drawing the lower ends of the levers 19 forwardly and moving the side members 16 and the rod 15 downwardly. The movement of the rod 15 is yieldingly transmitted through the springs 14 and the arms 13 and 10 to such of the bars 3 as are at liberty to rise. When the operator releases the handle upon the completion of the forward stroke, the handle is returned to its normal position (shown in dotted lines in Fig. 1) by a contractile spring 28^a (Figs. 5 and 10) connected at one end to the right-hand lever 19 and at its other end to an arm 28^b fixed to the shaft 26.

The means for positively moving down those type bars 3 which were raised in the forward stroke of the handle comprises a transverse rod 29 (Figs. 1 and 5) overlying the forward portions of the arms 10. For a complete disclosure of said means reference may be had to my application Serial

No. 670,665, filed October 25, 1923. During the rearward stroke of the handle 27 the restoring rod 29 is drawn downwardly in proper time relation to the operation of the printing mechanism, thus pushing down those type bars 3 that were raised to print an item or a total.

The means herein shown for limiting the extent to which the type bars 3 may rise, and thus to determine which numerals shall be brought to the printing position, comprises a stationary group of stops 42 (Fig. 1) similar to those employed in the Sundstrand adding machine. For a disclosure of the stop mechanism reference may be made to the Sundstrand Patent No. 1,198,487 and to my application Serial No. 409,778, filed September 13, 1920 (now Patent No. 1,583,102, dated May 4, 1926). It will here be sufficient to say that each stop is horizontally slideable in a forward and back direction, there being one vertical row or column of nine stops for each numerical order. When moved rearwardly from the position shown in Fig. 1, the stops are in the path of movement of devices carried by the type bars 3 and thereby limit the upward movement of said bars. These devices consist of arms 45 pivoted to the lower portions of the type bars 3, and pins 46 having openings through which the arms 45 extend. The pins 46 are guided for vertical movement in a slide 47 which is mounted on a stationary guide rod 48 extending transversely of the machine. The guide rod 48 is so positioned with reference to the group of stops 42 that the slide 47 is movable to carry the pins 46 from their normal or initial position at the left-hand side of the group of stops 42 into vertical alignment with the columns of stops. 105

The type bars 3 are normally about one step below the cipher-printing position, a slight movement being necessary to raise the pins 46 against the naught stops 42 or the detent plate 48^a described in Patent No. 1,198,487. When a bar 3 is raised until its pin 46 stops against a projected stop 42 in the second horizontal row from the bottom, said bar is in position to print the numeral "1". The stops 42 in the third row from the bottom serve to position the type bars for the printing of the numeral "2", and so on. As fully disclosed in said Patent No. 1,198,487, those type bars 3 which are not needed in printing a given item are prevented from rising when the handle is pulled forward, by the detent plate 48^a (Fig. 11) guided to move in a horizontal plane, said plate being connected through a bar 48^b to a rigid frame 48^c. The frame 48^c is mounted to swing on the axis of the bar 5 and is normally impelled forward by contractile springs 48^d, only one of which is shown in the present drawings. When the slide 47 is in the initial position (that is to 130

say, at the left-hand side of the machine) the 5 detent plate 48^a is out of the vertical plane of the pins 46. As soon as the slide moves one step to the right the detent plate 48^a is moved back far enough to overlie all the pins 46 except the one farthest to the right, as explained in my said Patent No. 1,583,102.

The means for projecting the stops 42 into 10 the path of the pins 46 comprises ten keys 49 which are numbered from "0" to "9", as shown in Fig. 2. The means whereby movement of the numeral keys 49 is transmitted to the stops 42 may be of any suitable character, as, for example, that disclosed in said Sundstrand Patent No. 1,198,487 or that shown in my said Patent No. 1,583,102.

The repeat or multiplying key 84 (Fig. 2) may be constructed and arranged in the 20 manner fully disclosed in said Sunstrand Patent No. 1,198,487.

In case the operator, when setting up an item, should strike a wrong numeral key, he 25 may correct the error by operating the back spacer key 86 (Fig. 2) to restore the slide 47 to the position occupied just before the error occurred. The back spacer key 86 may be connected to the slide 47 as in Patent No. 1,198,487. The back spacer key 30 may also be employed when it is desired to set the slide 47 for the printing of a number one-tenth that of the number previously set up.

The calculating mechanism comprises two 35 series of pinions 125 and 125^a (Figs. 18 and 19), each series being rotatably mounted upon a transverse shaft 126. For convenience, the rear series of pinions 125 will be herein termed the debit totalizer, and the 40 forward series of pinions 125^a the credit totalizer. There are as many pinions in each totalizer as there are type bars 3. The shafts 126 are supported for sliding movement longitudinally of the machine. For 45 this purpose the ends of the shafts 126 are carried by two parallel plates 127 (Figs. 15 and 21). The ends of said plates have slots 128 to receive two transverse guide bars 129 which are rigidly secured to the stationary 50 framework of the machine. The totalizers are located between two sets of racks 130 and 131 which are connected to the type bars 3.

Addition of debit items is accomplished 55 by means of the rear totalizer and the set of racks 130. When a debit item is to be added, the plates 127 are moved to place both totalizers out of mesh with the racks before the type bars 3 are raised; and are moved 60 rearwardly to place the rear totalizer in mesh with the racks 130 just before the bars 3 are moved downwardly. Addition of debit items therefore occurs in the down stroke of the racks 130, the extent of rotation of the pinions depending, of course,

upon the extent of movement of the type bars 3 and racks 130.

Addition of credit items is effected by means of the front totalizer and the set of racks 131. When a credit item is to be 70 added, the plates 127 are moved to place both totalizers out of mesh with the racks before the type bars 3 are elevated; and are moved forward to place the front totalizer in mesh with the racks 131 just before the 75 type bars 3 descend. Addition of credit items consequently takes place in the down stroke of the racks 131.

The upper end of each rack is attached to a rearwardly extending portion 132 (Fig. 80 18) of one of the type bars 3 by means of a headed pin or stud 133 extending through a vertically elongated opening 134 in the rack. A contractile spring 135 attached at its upper end to the rack at 136 and at its 85 lower end to a downwardly-extending portion 137 of the type bar tends to move the rack downwardly with relation to the type bar one tooth space for carrying purposes. The backs of the racks slide in grooves 138 90 (Fig. 20) in the stationary guide bars 129. The part 136 of the rack being virtually a short lever arm, the spring 135 tends to turn the rack on the stud 133 as a pivot, and thus 95 serves to hold the rack in place in its guide groove 138. However, in order to prevent the rack from being pulled out of place in case the pinion teeth should stick thereto when the pinion is being moved toward 100 neutral position, I provide a bar 139 fixed in the framework and extending adjacent to and transversely of the racks. Normally, there is clearance between the racks and the bars 139.

The guide bars 129 are located close to the 105 point of tangency of the racks to the pinions, and hence serve effectively to guide the racks. Even if the racks were slightly bent or bowed, or if there were a tendency to move in a non-rectilinear path, they would be compelled to reciprocate in proper relation to the pinions.

The totalizers are moved into and out of mesh with the racks 130 and 131 by means 110 of two links 140 (Figs. 14 and 21), one at each side of the machine, the forward ends of which are connected to the plates 127 by means of pivots 140^a. The rear ends of the links 140 are pivoted at 141 to the lower 115 arms of two levers 142 (Figs. 14 and 16) which are rigidly secured to a shaft 143 (Fig. 21) that is journaled in the framework of the machine.

The means for swinging the levers 142 to 120 move the pinions into and out of mesh with the racks comprises a link 144 (Fig. 14), the forward end of which is supported by a lever 145 pivoted on a rod 146. The rear 125 end of the link 144 is provided with notches 147 and 148 to receive pins 149 and 150, re-

spectively, on opposite ends of the right-hand lever 142. Rearwardly of the notches 147 and 148 are lugs 151 and 152, respectively, which serve to prevent disengagement 5 of the lever 142 from the link 144. Forwardly of the notches 147 and 148 are curved surfaces adapted to slide in contact with the pins 149 and 150. The link 144 is moved forward and back by means of an 10 oscillatory cam plate 153 having a cam slot 154 therein, the upper portion of said slot being concentric with the axis 155 of said plate. On the forward end of the link 144 is a roller 156 that lies in the slot 154. A 15 contractile spring 157 (Fig. 8) connected to the lever 145 and anchored to the machine frame holds the roller 156 against the front wall of the cam slot 154 and thus takes up play. The tension of the spring overcomes 20 the weight of the cam 153 and the link 144, and thus prevents the weight of these parts from causing the totalizers to move out of neutral position.

The means for oscillating the cam 153 comprises a pawl 158 (Fig. 14) which is pivoted at 159 upon a plate 160 which is rigidly secured to the arm 24. A contractile spring 161 (Fig. 8) is connected at one end to an extension of the pawl 158 and at its other 30 end to the plate 160. The pawl 158 has a shoulder 158^a (Fig. 11) adapted to engage a pin 162 (Fig. 11) set in the cam 153 at one side of its axis 155, and another shoulder 158^b adapted to engage a pin 163 fixed in 35 the cam 153 at the opposite side of its axis. There is a guide finger 164 on the pawl between the shoulders referred to, said guide finger extending into the space between the pins 162 and 163 so as to strike said pins as 40 the arm 24 swings, whereby the pawl is swung to one side or the other of its pivot. The spring 161 tends to swing the pawl into central position. Under certain conditions 45 the pawl 158 engages the pin 162 when the handle 27 is pulled forward, thereby swinging the cam 153 upwardly and drawing the link 144 forward, thus operating the levers 142 and consequently shifting the totalizers; and when the handle swings rearwardly, the pawl 158 engages the pin 163 and swings the cam 153 downwardly, thus 50 pushing the link 144 rearwardly, with a resultant shifting of the totalizers.

Referring now to the means for determining which totalizer shall be placed in engagement with its racks: When the machine is clear, the link 144 is in engagement with the lower pin 150, as in Fig. 13, the pinions 125 being then in mesh with the racks 130. Reciprocation of the link 144 will therefore 55 shift the pinions 125 into and out of mesh with the racks 130. When a credit item is to be added, the link 144 is shifted into 60 engagement with the upper pin 149, as in

Fig. 14. It will be seen that the link 144 is reciprocable in two different planes. The means for shifting the link 144 from one plane to another comprises a lever 165 (Fig. 14) pivoted at 166 in the machine frame and 70 having a forked rear end which engages a pin 167 on the link 144. The lever 165 has a downwardly-extending arm 168 to which is attached a contractile spring 169 that serves to raise the lever 165 and hence the 75 link 144. The spring 169 is controlled by means including a credit key 170 having a stem 171 which is guided for vertical movement. A contractile spring 172 normally holds the credit key elevated. On the stem 80 80 is a pin 173 that overlies a forwardly extending arm 174 pivoted at 175. Rigid with the arm 174 is a downwardly extending arm 176. A contractile spring 177 connected to the arm 176 tends to draw said arm forward. 85 When the credit key is depressed, the arm 176 is locked against actuation by the spring 177, by means of a finger 178 fixed to one end of a rock shaft 179 and adapted to overlie the arm 174. Said shaft is arranged to 90 be operated to release the arm 174 in the manner disclosed in said application Serial No. 670,665. The finger 178 also serves to lock the credit key down, there being a hook 180 (Fig. 14) rigid with the arms 174 and 176 which is adapted to engage a pin 181 on the stem 171.

To the lower end of the arm 176 is pivoted a link 182 which has a lost-motion connection with the arm 168 consisting of a 100 headed stud 183 on the arm 168 extending through an elongated hole 184 in the link. The contractile spring 169 is anchored to the link 182, as shown in Fig. 4.

Assuming that the machine is clear, or 105 that one or more debit items have just been accumulated, the link 144 will be in engagement with the lower pin 150, as shown in Fig. 13. If a credit item is to be registered, the credit key 170 is depressed after the 110 credit item has been set up, thereby pushing the link 182 rearwardly and thus moving the rear end wall of the opening 184 away from the stud 183. When the handle 27 is pulled, the link 144 is drawn forward, as before explained, to withdraw the pinions 125 from the racks 130 before the racks rise. The forward movement of the link 144 causes the lever 142 to rock, as a result of which the pin 149 is brought into register with the 120 notch 147. Thereupon the spring 169 draws the arm 168 rearwardly, thus placing the notch 147 in engagement with the pin 149. In the return stroke of the handle (Fig. 14), the link 144 is pushed rearwardly, thereby 125 rocking the lever 142 in the direction to place the pinions 125^a in mesh with the racks 131 before the latter start down. The upper portion of the slot 154 in the cam 153 is a dwell, consequently the return of the handle 130

27 to its initial position leaves the pinions 125^a in mesh with the racks 131. The notch 147 also remains in engagement with the pin 149, inasmuch as the link 144 rests upon the 5 pin 150. The credit key 170 is released through automatic operation of the rock shaft 179. The release of the arm 174 by the finger 178 allows the spring 177 to turn the three-arm lever 174-176-181 far 10 enough to release the credit key 170, the action of the spring being limited by engagement of the rear end wall of the opening 184 with the stud 183.

If the next item to be added be a debit 15 item, the notch 148 is placed in engagement with the pin 150 in the following manner: In the forward stroke of the handle, the link 144 is drawn forward to place the totalizers in central position before the racks ascend. 20 As soon as the pin 150 comes into register with the notch 148, the spring 177 pulls the link 182 forward, the rear end wall of the opening 184 causing the arm 168 also to move forward, and thereby lowering the link 25 144 so as to place the notch 148 in engagement with the pin 150. It will, of course, be evident that the weight of the link 144 and the lever 165 assists to cause engagement of the notch 148 with the pin 150. In the 30 return stroke of the handle, the link 144 is pushed rearwardly by the cam 153, whereby the lever 142 is swung in the direction to place the pinions 125 in mesh with the racks 130 before the racks descend.

35 It will be noted that the link 144 is shifted into and out of engagement with the pins 149 and 150 when the totalizers are in central position, that is to say, out of mesh with the racks.

40 To prevent casual rotation of the pinions while they are out of mesh with the racks, I provide for each totalizer a bar 185 (Fig. 14) extending longitudinally of the series of pinions and adapted to enter between the 45 teeth thereof. Said bar is rigid with two arms 186 which are pivoted on the plates 127 at 187 (Fig. 15). At the free ends of the arms 186 are pins 188 (Fig. 8) which lie in cam slots 189 (Fig. 17) in two cams 190 pivoted at 191 in the stationary framework of the machine. The cam slot 189 in each cam 190 is below the pivot 191. Above the pivot is a notch 192 to receive the projecting end of the studs 140^a by means of 50 which the links 140 are connected to the plates 127. Upon reference to Fig. 3, it will be observed that when the pinions are out of mesh with both sets of racks, the pins 188 are in the central dwell portions of the 55 slots 189, and that upon movement of the pinions in either direction, the cams 190 will swing and will cam the pins 188 down, thus withdrawing the locking bars 185 from the pinions.

Referring now to the transfer mechanism 65 (best shown in Figs. 18 and 19): For each totalizer, there is a separate set of transfer devices. It has been explained that the type bars 3 are moved to their normal lower position by the rod 29. The extent of downward movement of the type bars 3 is limited 70 by the rod 5. The extent of downward movement of the racks is limited (except in the transfer operation) by contact of lugs 193 on the racks with stop lugs 194. When 75 an amount is to be transferred from one order to the next higher order, the stop lug 194 for the rack belonging to such higher order is withdrawn, thereby allowing that rack to descend under the action of its 80 spring 135 until its lug 193 stops against the bar 129 as indicated in the right-hand portion of Fig. 18 and the left-hand portion of Fig. 19. The extent of such further descent of the rack is just sufficient to turn 85 the pinion for that rack through the distance of one tooth. Each stop lug 194 is formed on an arm or pawl 195 which is suspended from a pivot 196 in the framework 90 of the machine, said pivot being above the horizontal plane of the pinions. To the lower end of each pawl 195 is pivoted a dog 197 having a tooth 198 adapted to engage the edge of the adjacent bar 129. There is a 95 dog 197 at the right-hand side of each rack except the units rack. The dog 197 lies within a horizontal groove 199 (Fig. 20) in the bar 129. A contractile spring 200 normally holds the tooth 198 in engagement with the bar 129, the stop lug 194 being then 100 in position to support the rack at the left of the dog 197.

The means for disengaging the tooth 198 from the bar 129 consists of a lug 201 (Fig. 21) fixed to the left side of each pinion. When the amount registered by a pinion reaches 9, continued rotation of the pinion as the rack descends brings the lug 209 against the end of the dog 197, thereby depressing the dog until the tooth 198 is clear 105 of the bar 129, whereupon the spring 200 (assisted by the downward pressure of the rack) pulls the dog and the pawl 195 away from the rack until a lug 202 on the dog 110 115 stops against a restoring rod 203. The lug 194 is then out of the path of the rack of the next higher order, and the latter therefore moves down under the influence of its spring 135 until stopped by the bar 129.

120 After each transfer operation the pawl 195 and the dog 197 are restored to their normal position by the rod 203, there being one such restoring rod for each of the sets of transfer mechanism. Each rod 203 is carried by two bell crank levers 204 which are pivoted in the framework of the machine at 196. The bell crank levers at each side of the 125 machine are connected for simultaneous

swinging movement by a pin and slot connection, as shown at 205 in Fig. 19. The restoring rods 203 are simultaneously moved toward and away from each other by means 5 of two arms 206 each formed integral with one of the bell crank levers 204, said arms 206 extending into the space between the side members 16. A rod 207 (Fig. 1), the ends of which lie in elongated openings 208 in the 10 side members 16 is normally held against the lower end walls of said openings by means of two springs 209 extending between said rod and the rod 15. One of said springs is shown in Fig. 1. When the side members 15 16 move downwardly in the forward stroke of the handle 27, (and hence as the type bars 3 are moving upwardly), the rod 207 is carried into engagement with the arms 206, thereby causing the rods 203 to move toward 20 each other to restore any transfer devices that may have been concerned in a previous transfer operation. When the side members 16 rise, a contractile spring 210 (Fig. 19) returns the rods 203 to the normal position 25 shown in said view. Such normal position is determined by contact of the bell crank levers 204 with the stop rods 139 (Fig. 18).

When the type bars are raised for a printing operation, the racks do not begin to rise 30 until the studs 133 (Fig. 18) engage the upper ends of the elongated openings 134. Those racks, however, which have descended below the normal position, in order to effect 35 a transfer, rise practically simultaneously with the type bars, and thus are lifted before the stop lugs 194 are restored to normal position by the rod 203. So, also, the movement imparted to the type bars during the enforced spacing stroke of the handle 27 is 40 sufficient to raise the lugs 193 to permit the placing of the stop lugs 194 thereunder. (For a disclosure of one form of enforced spacing stroke mechanism suitable for use in this machine, reference may be had to my 45 Patent No. 1,583,102.)

It may be here stated that when any pinion stands at zero, the lug 201 on said pinion lies directly beneath the dog 197 at the left 50 of said pinion. Therefore, when a total is to be printed, those racks which mesh with the pinions standing at zero cannot rise, the remaining racks rising until the rotation of their pinions brings the lugs 201 thereon into contact with the respective dogs 197. The 55 type bars 3 are then in position to print the total amount accumulated on the pinions.

The herein-described arrangement of racks and pinions, with springs 135 anchored to a downward extension of the type bar lying 60 between the racks, and cross-bars 129 serving the double function of guiding the racks and cooperating with the transfer dogs 197, has solved the problem of introducing a duplex adding mechanism into an adding machine

of the Sundstrand type without increasing 65 the over-all dimensions of the latter.

As hereinbefore stated, when an item is to be added, the totalizer into which the item is to be introduced is out of mesh with its racks during the upward movement of the latter 70 and is in mesh with the racks during their descent. When a total is to be taken, the totalizer remains in mesh with the racks during the rising movement of the latter. It will be remembered that the means for placing the totalizers in and out of mesh with their racks includes the cam 153 and the pawl 158 (Fig. 14). The means for controlling the pawl 158 so as to determine whether the totalizer shall be in or out of mesh during 75 the upward and downward movements of the racks will now be described.

The means for controlling engagement of the pawl 158 with the pin 162 includes an arm 211 (Fig. 11) pivoted at 212 in the machine frame, the upper end of said arm having an angular lug 213 adapted to hold the pawl 158 out of position to engage said pin. In the arm 211 is an elongated opening 214 in which lies a pin 215 fixed to the swinging frame 48^e. As explained in the Sundstrand Patents Nos. 1,198,487 and 1,583,102, when there is no number set up in the group of stops 42, the frame 48^e is in its forward position. As soon as a digit is set up in the machine, the frame 48^e swings back, thereby swinging the arm 211 rearwardly away from the pawl 158 and leaving said pawl in position to engage the pin 162 when the handle 27 is pulled. After a spacing stroke of the handle, the frame 48^e is in its forward position, and the pawl 158 is held out of engagement with the pin 162; consequently the cam 153 is not moved during the forward stroke of the handle 27, and the debit totalizer remains in mesh with its racks during the rise of the latter, thereby effecting the positioning of the type bars for the printing of the debit total. The printing of the debit total is thus automatic, that is to say, without any manipulation other than the operation of the handle 27. The printing of a credit total, however, requires depression of the credit key 170, as will appear hereinafter. 110

When it is not desired to clear the totalizer after printing a total, the totalizer is allowed to remain in mesh with its racks during the downward movement thereof, and therefore during the downward movement of the racks the several pinions of the totalizer are rotated to the positions they occupied just before the taking of the total. When, however, the operator wishes to clear the totalizer, the latter is withdrawn from its racks before the racks descend. The means for swinging the cam 153 to effect such movement of the pinions comprises a lever 216 (Figs. 4 and 11) pivoted on the 115 120 125

shaft 26 and having a cam slot 217 in which lies a roller 218 on the cam 153. The lever 216 has an arm 219 which is arranged to be engaged by a pin 220 (Fig. 12) on the arm 24.

During adding operations and during the enforced blank stroke of the handle 27 the cam 153 is swung by the pawl 158, and the lever 216 swings idly; but when one of the totalizers is to be cleared, the pawl 158 is held out of action, and the cam 153 is swung by the lever 216 at the beginning of the return stroke of the handle, so as to withdraw the totalizer from its racks before the latter descend, whereby the pinions are left standing at zero. The means for swinging the lever 216 forward to disengage the totalizer from the racks is controlled by a clear or total key 221 (Fig. 4) having a stem 222. On the stem 222 is a stud 223 that underlies the forward end of a lever 224. The lever 224 has an elongated opening 225 through which a pivot rod 226 extends, the lever 224 thus being movable longitudinally to a slight extent. A contractile spring 227 tends to slide the lever 224 rearwardly. 228 (Fig. 8) is a contractile spring stretched between a pin on the stem 222 and the front end of the lever 224 and tending to hold the stud 223 and the lever 224 in contact with each other. During the printing of an item and during the enforced blank or spacing stroke prior to the taking of a total, the lever 224 is held against movement by the spring 228 by means comprising a cam plate 229 (Fig. 8) which is pivoted at 230 and is acted upon by a contractile spring 231. On the rear end of the lever 224 is a pin 232 underlying the cam plate 229. The spring 231 normally holds the cam plate 229 in contact with a sleeve or antifriction roller 233 (Fig. 5) on a stud 234 carried by the adjacent lever 19. The movement of the cam plate 229 under the influence of the spring 231 is restrained at times by a detent arm 235 (Figs. 4 and 7) pivoted at 236 in the framework of the machine and normally held by a contractile spring 237 in contact with the stud 234 (Fig. 5). On the detent arm 235 is a pin 238 (Fig. 7) adapted to engage a hook 239 (Figs. 4 and 8) on the cam plate 229. At times the detent arm 235 is prevented from moving under the influence of the spring 237 into position where the pin 238 is in front of the hook 239, by means of a pin 240 (Figs. 4 and 11) on an arm 241 which is rigid with the arm 211. The upper end of the arm 235 is cut away so as to clear the pin 240 when the arm 211 is in its rearward position (as it is when an item has been set up or an enforced blank stroke is to be taken).

A detent plate 242 (Fig. 9) pivoted on the center 230 has a cam slot 243 having a dwell portion 244 in which the roller 233

(Fig. 5) is arranged to run. That portion 65 of the pin 232 which projects from the inner side of the lever 224 underlies the plate 242 (see Fig. 5). In the lower edge of the plate 242 is a notch 244 (Fig. 9).

It will be remembered that the roller 233 70 and the stud 234 are connected to swing back and forth with the handle 27. Even if the total key were held depressed while the handle was being drawn forward to print an item, or take an enforced blank 75 stroke, the lever 224 would be held against movement by the spring 228, by the cam plate 229 overlying the pin 232; the spring 231, in turn, being prevented from moving the cam plate 229 by means of the pin 238. 80 But after the blank stroke has been taken, the swinging frame 48^c (and consequently the arm 241) are in their forward position, and therefore if the total key 221 be depressed, the cam plate 229 is free to follow 85 the roller 233 as the handle is drawn forward to clear the machine, until the pin 232 on the rear end of the lever 224 has risen under the influence of the spring 228 until said pin 232 is in a locking notch 245 90 (Fig. 8) in the cam plate 229. The pin 232 does not enter said notch 245 until the movement of the plate 242 (Fig. 9) under the action of the roller 233 has brought the notch 244 into register with said pin 232, 95 whereupon the pin 232 enters the notches 244 and 245. Very shortly after the handle 27 has commenced its return stroke, the roller 233 acting on the walls of the cam slot 243, swings the plate 242 downwardly, 100 thus pushing the pin 232 and the lever 224 forwardly. On the lever 224 is a shoulder 246 (Figs. 4 and 8) adapted to engage a pin 247 on the lever 216 when the lever 224 is tilted by the spring 228. When the lever 105 224 is pushed forward by the plate 242, the shoulder 246 pushes the lever 216 forward, thereby swinging the cam 153 upwardly, thus pulling the link 144 forward, and hence moving the totalizer out of mesh with its 110 racks. As before indicated, this occurs during the early part of the return movement of the handle 27 and before the racks descend, the pinions being therefore left standing at zero. As the roller 233 continues on its return stroke, it swings the cam plate 229 against the tension of the spring 231, the lower edge of said plate positively camming the pin 232 down, and thus, in conjunction with the spring 227, restoring 115 120 the lever 224 to its initial or inoperative position. As the arm 24 (Fig. 11) returns to its initial position, the pin 220 (Fig. 12) thereon engages the arm 219 and restores the lever 216 to its initial position.

When the totalizer was withdrawn from its racks, the type bars used in printing the total rose to the top limit of their movement,

under the influence of the springs 14. In the continuation of the back stroke of the handle 27, the racks are drawn down to normal position by the rod 29, as before 5 explained.

It is sometimes desirable to print an item without adding it, particularly when a laterally shiftable paper carriage is employed and designating numbers are to be printed 10 in the left-hand column. Non-addition of such designating numbers (a total of which would be meaningless) may be accomplished (in the case of the rear totalizer) by means acting to prevent the pawl 158 (Fig. 8) from 15 engaging the pin 163, so that the rear totalizer shall not be thrown into mesh with its racks 130 at the beginning of the down stroke. A slide 255 (Fig. 8) is mounted on two guide studs 256 for movement longitudinally of the machine, the slide being slotted at 255^a to receive said studs. On the slide 255 is a cam surface 257. A contractile spring 258 tends to draw the slide 255 rearwardly to bring the cam surface 257 into 20 such position that when the pawl 158 is carried forward a pin 259 on said pawl shall engage the surface 257, thus holding the pawl down so that on its return stroke the shoulder 158^b (Fig. 14) shall be unable to 25 engage the pin 163. The slide 255 is normally locked in its forward position by a stud 260 (Fig. 8) on a bell crank 261 pivoted on the axis 226. A contractile spring 262 normally holds the bell crank in such 30 position that the stud 260 lies behind a lug 263 on the slide 255. The means for withdrawing the stud 260 from said lug comprises a non-add key 264 having a stem 265 which is guided for vertical movement. On 35 the stem 265 is a pin 266 that overlies a lug 267 on the bell crank 261. The spring 228 that normally holds the total key up serves also to hold the non-add key elevated, there being a lug 268 on the total key stem which 40 underlies the pin 266. The non-add key is locked in depressed position by means of a lever 269 (Fig. 6) pivoted at 270 and having a notch 271 to receive a pin 272 (Fig. 4) on the non-add key stem. The free end 273 of 45 the lever 269 is arranged to be engaged by the locking finger 178 (Fig. 4).

The slide 255 is restored to its forward position by means of the lever 274 (Fig. 4) that actuates the ribbon feed mechanism, the 50 lower end of said lever lying behind the rear end of the slide. The lever 274 is connected to the adjacent lever 19 through a link 275.

When a number is to be printed, but not added, the operator depresses the non-add 55 key 264 and pulls the handle 27 forward. Depression of the non-add key withdraws the stud 260 from the lug 263. As the handle 27 swings forward, the ribbon-feed lever 274 swings rearward, thus allowing the

spring 258 to draw the slide 255 to its rearward position, that is to say, until the end walls of the slots 255^a stop against the studs 256. As the handle 27 makes its forward swing, the pin 259 on the pawl 158 engages the cam surface 257, whereby the pawl is depressed to such an extent that on the return stroke of the pawl it fails to engage the pin 163. The totalizer therefore is not thrown into mesh with its racks at the beginning of the downward stroke of the latter, and consequently the number set up and printed is not added. As the handle makes its rearward swing, the pin 220 (Fig. 12) on the arm 24 engages the arm 219 and restores the lever 216 to initial position, thereby returning the pinions into mesh with the racks. In the return stroke of the handle, the lever ribbon-feed 274 pushes the slide 255 forward to its normal position, as in Fig. 4. As the handle is approaching its initial position, 85 the locking finger 178 (Fig. 4) is disengaged from the arm 273 of the lever 269, whereupon the non-add key springs up to its normal position, thus allowing the spring 262 (Fig. 8) to place the stud 260 behind the 90 lug 263 on the slide 255.

In actual practice, there is no occasion for printing a credit item without also adding it, hence no provision is made for preventing accumulation when the credit totalizer is in 95 use.

The hammer mechanism and the sign-printing mechanism may be of any suitable character, as, for example, that fully disclosed in my said application Serial No. 100 670,665, and therefore need not be here described.

The machine is preferably arranged to print items and totals in contrasting colors, as, for example, items in blue and totals in 105 red. The means for shifting the ribbon to print in the desired color may be of any suitable character, as, for example, that employed in the Sundstrand Patent No. 1,198,-487, and therefore has not been disclosed 110 herein in detail.

If desired, means may be provided for printing a distinguishing character in connection with certain imprints, as, for example, in connection with a credit item, a 115 final debit total, a credit total, or an item which is printed but not added to the previous items; or to indicate that either or both totalizers are clear. Herein is shown a special sign-printing bar 3' (Figs. 8 and 14) 120 which is constructed and operated substantially as disclosed in application Serial No. 670,665. It will be understood that any appropriate sign may be substituted for the credit sign herein shown.

When it is desired to add an amount without printing it, the hammer mechanism may be disabled by means comprising a non-

print key 348 (Fig. 2), as fully described in application Serial No. 670,665.

The capabilities of the machine are indicated by the facsimiles of printed matter 5 constituting Figs. 22 to 25. In these views dotted lines are used to denote red imprints.

Referring first to Fig. 22, the red imprint *a* is a sign indicating that the debit totalizer is clear and the red imprint *b* is a sign 10 denoting that the credit totalizer is clear. These signs are printed by depressing the keys 170 and 221, pulling the handle, releasing said keys and pulling the handle again. Fig. 22 shows that four debit items were 15 printed and accumulated in the debit totalizer. In setting up, registering and printing the next item (which is a credit item of 12¢) the operator set up the item on the keyboard, depressed the credit key 170 and 20 pulled the handle, thus printing the item, together with its distinguishing sign, and introduced the item into the front or credit totalizer. The same operations were 25 repeated in connection with the next three items, the credit key 170 being depressed before or after the setting up of each credit item. A final total of the debit items and a 30 final total of the credit items is then obtained by first taking a blank or spacing stroke of the handle, then depressing the credit key 170 and the clear or total key 221, pulling the handle a second time (whereby the debit total of 1.22 is printed in red, together with the debit clear sign, and the 35 debit totalizer cleared), and pulling the handle a third time, whereby the credit total of 1.13 is printed in red, together with the credit sign, and the credit totalizer cleared.

The operations that occurred during these 40 three reciprocations of the handle will now be described.

The addition of the last credit item of .20 left the credit totalizer standing in mesh with the racks 131 and the link 144 in engagement with the upper pin 149 (Fig. 14). In the forward stroke just referred to as the "blank or spacing stroke", the pawl 158 engaged the pin 162 and swung the cam 153 up, thus pulling the link 144 forward and 50 thereby moving the totalizers rearwardly into central position. As the link 144 completed its forward movement it slipped down into engagement with the lower pin 150. In the ensuing return stroke of the 55 handle, the link 144 was pushed rearwardly, thus placing the debit totalizer in mesh with its racks 130; and the detent plate 48^a moved forward out of the way of the pins 46, the arm 211 (Fig. 11) moving forward so as to hold the pawl 158 out of position to engage the pin 162. The credit and clear keys were then depressed.

During the following forward stroke of the handle, the pawl 158 being held out of

action by the arm 211 (Fig. 11), the debit totalizer remained in mesh with the racks 130 during their upward movement. During the initial portion of the following return movement of the handle, the slide 255 prevented the pawl 158 from engaging the pin 163; and the roller 233, through the agency of the cam plate 242, pin 232 and levers 224 and 216, swung the cam 153 up, thereby withdrawing the debit totalizer from the racks 130 before they descended and thus 75 leaving said totalizer cleared. Such withdrawal of the debit totalizer from the racks 130 was caused by forward movement of the link 144, in the course of which the upper pin 149 (Fig. 13) came into register 80 with the notch 147, whereupon the spring 169 raised the link 144 to place said notch and pin in engagement with each other. During the latter portion of the return stroke of the handle, the pin 220 (Fig. 12) 85 on the arm 24, acting through the arm 219 and the lever 216, restored the cam 153 to its normal down position, thereby pushing the link 144 rearwardly and placing the credit totalizer in mesh with the racks 131. 90

The handle being pulled the third time, with the clear and credit keys held depressed, the pawl 158 being held out of action by the arm 211, the credit totalizer remained in mesh with the racks 131 during 95 their upward movement. During the early part of the ensuing return stroke of the handle, the slide 255 prevented the pawl 158 from engaging the pin 163; and the roller 233, cam plate 242, pin 232, and levers 224 100 and 216 raised the cam 153, thereby withdrawing the credit totalizer from the racks 131 before they descended and thus leaving said totalizer cleared. Such withdrawal of the credit totalizer was effected by forward 105 movement of the link 144. During the latter part of the return stroke of the handle, the pin 220 on the arm 24, acting through the arm 219 and the lever 216, returned the cam 153 to its down position, thereby pushing the link 144 rearwardly, the notch 147 remaining in engagement with the upper pin 149, and the credit totalizer being thus 110 returned into mesh with the racks 131.

Fig. 23 shows that the machine may be 115 used for alternately printing items of two different classes. It will be apparent that in a machine provided with a laterally-shiftable paper carriage arranged to occupy one position when printing items of one class and another position for items of the other class, the items will be printed in parallel columns. If desired, the rear totalizer may be used in printing a designating number 120 opposite each number printed with the front totalizer, such designating numbers being 125 non-accumulated.

Fig. 24 indicates that the machine may be

used to take a subtotal from the rear or debit totalizer. The operation of registering and printing the debit item of 5.67 left the rear totalizer in mesh with its racks 130, and the 5 notch 148 in engagement with the pin 150, as shown in Fig. 13, the detent plate 48^a being in its rear position where it prevents rising movement of the type bars 3. It being desired to obtain a final total from the 10 credit totalizer and a subtotal from the debit totalizer, the operator depresses the credit key 170 and pulls the handle 27. In the course of the forward stroke of the handle the pawl 158 engages the pin 162 and lifts 15 the cam 153, thereby pulling the link 144 forward and thus placing the totalizers in central position. As soon as the upper pin 149 and the notch 147 come into register with each other, the spring 169 lifts the link 144 20 into engagement with said pin. In the return movement of the handle the pawl 158 engages the pin 163, thereby swinging the cam 153 downward and pushing the link 144 rearward, thereby moving the front 25 totalizer into engagement with the racks 131. The detent plate 48^a also was moved forward out of the way of the pins 46, thereby causing the arm 211 (Fig. 11) to swing forward 30 into engagement with the pawl 158. The operator then depresses the clear or total key 221, and pulls the handle a second time. The pawl 158 being prevented from engaging the pin 162, the cam 153 remains in its down 35 position; consequently, the credit totalizer remains in mesh with its racks while the latter rise to printing position, their ascent being limited by engagement of the lugs 201 (Fig. 21) with the front set of pawls 197. In the initial portion of the return movement 40 of the handle the hammers are released to print the credit total of 6.12 and the credit sign; the slide 255 prevents the pawl 158 from engaging the pin 163 and the roller 233 swings the cam 153 up, thereby 45 pulling the link 144 forward and thus withdrawing the credit totalizer from the racks 131 before the latter descend, and hence leaving the credit totalizer clear. In the movement of the link, the pin 150 is moved into 50 register with the notch 148, whereupon the link 144 drops into engagement with said pin, as shown in Fig. 13. During the latter part of the return stroke of the handle, the pin 220, arm 219 and lever 216 restore the 55 cam 153 to initial position and thus move the link 144, thereby placing the debit totalizer in mesh with the racks 130. The total key 221 rises under the influence of the spring 228 as the lever 224 returns to normal position. The detent plate 48^a and the arm 211 60 being still in their forward position, when the operator again pulls the handle the pawl 158 is prevented from engaging the pin 162, consequently the cam 153 remains in initial 65 position and the debit totalizer remains in

mesh with the racks 130 during their rising movement (whereby the racks 130 are positioned for printing the debit total 8.46) and during the descent of the racks.

In the specimen of work reproduced in Fig. 25, the debit items have been cleared from the rear totalizer from time to time, while the credit items have been retained in the front totalizer until the end of operations. 75

It will be understood that the front totalizer has been called the credit totalizer merely for convenience, and that it may be used to receive items of various classes.

It will be apparent that the rear totalizer may be used in calculations involving subtraction, multiplication and division in the manner commonly employed in ordinary so-called adding machines. 80

While the present embodiment of the invention has been described in considerable detail, it should be understood that the invention is not limited to the particular construction and arrangement of the parts and mechanisms shown, and that various modifications coming within the scope of the appended claims will suggest themselves to those skilled in the art. 85

I claim as my invention:

1. An adding and recording machine, having, in combination, a set of vertically reciprocatory type bars each having a rearward extension, two sets of racks facing each other, each rack having a stud and slot connection with one of said extensions, said extension having a downwardly extending portion between the racks, contractile springs connecting said racks to said portion and tending to move the racks down, two totalizers located between the sets of racks, each totalizer being arranged to mesh with a particular set of racks, said totalizers being connected together to move as a unit into and out of mesh with the racks, means for moving said totalizers into and out of mesh with the racks in adding operations, means for modifying the action of said totalizer-moving means so as to place a selected totalizer in action, means for modifying the action of said totalizer-moving means so as to obtain totals, and means to modify the action of said totalizer-moving means so as to prevent accumulation. 90

2. An adding and recording machine having, in combination, a set of vertically reciprocatory type bars each having a rearward extension, two sets of racks facing each other, each rack having a stud and slot connection with one of said extensions, said extension having a downwardly-extending portion between the racks, contractile springs connecting said racks to said portion and tending to move the racks down, two totalizers located between the sets of racks, each totalizer being arranged to mesh with a particular set of 100

- racks, said totalizers being connected together to move as a unit into and out of mesh with the racks, means for moving said totalizers into and out of mesh with the 5 racks in adding operations, means for modifying the action of said totalizer-moving means so as to place a selected totalizer in action, and means for modifying the action of said totalizer-moving means so as to obtain totals. 10 including two independent sets of transfer devices, one for each set of racks.
3. An adding and recording machine, having, in combination, a set of vertically reciprocatory type bars each having a rearward extension, two sets of racks facing 15 each other, each rack having a stud and slot connection with one of said extensions, said extension having a downwardly extending portion between the racks, contractile springs connecting said racks to said portion and 20 tending to move the racks down, two totalizers located between the sets of racks, each totalizer being arranged to mesh with a particular set of racks, said totalizers being connected together to move as a unit into and 25 out of mesh with the racks, means for moving said totalizers into and out of mesh with the racks in adding operations, and means for modifying the action of said totalizer-moving means so as to place a selected totalizer in action. 30
4. An adding and recording machine having, in combination, a set of vertically reciprocatory type bars each having a rearward extension, two sets of racks facing each other, 35 each rack having a stud and slot connection with one of said extensions, said extension having a downwardly extending portion between the racks, contractile springs connecting said racks to said portion and tending 40 to move the racks down, two totalizers located between the sets of racks, each totalizer being arranged to mesh with a particular set of racks, said totalizers being continually out of mesh with each other, said totalizers being connected together to move as a 45 unit into and out of mesh with the racks, and means for moving said totalizers into and out of mesh with the racks. 50
5. An adding and recording machine having, in combination, a set of vertically reciprocatory type bars each having a rearward extension, two sets of racks facing each other, each rack having a stud and slot connection with one of said extensions, said extension having a downwardly extending portion between the racks, contractile springs connecting said racks to said portion and tending to move the racks down, two totalizers located between the sets of racks, each totalizer being arranged to mesh with a particular set of racks, said totalizers being connected together to move as a unit into and out of mesh with the racks, means for moving said totalizers into and out of mesh with the racks, and carrying means 60
6. A computing and recording machine having, in combination, a set of reciprocatory type carriers, two sets of racks facing each other and connected to said type carriers, two totalizers located between the sets of racks, each totalizer being arranged to mesh with a particular set of racks, said totalizers being continually out of mesh with each other, and means for moving said totalizers into and out of mesh with the racks. 70
7. A computing and recording machine having, in combination, a set of reciprocatory type carriers, two sets of racks facing each other and connected to said type carriers, two totalizers located between the sets of racks, means for moving said totalizers into and out of mesh with the racks, and carrying means including two independent sets of transfer devices, one for each set of racks. 75
8. A computing and recording machine having, in combination, a set of reciprocatory type carriers, and accumulating means including two sets of racks facing each other and connected to said type carriers, two totalizers located between the sets of racks, and means for moving said totalizers into and out of mesh with the racks. 80
9. A computing and recording machine having, in combination, a set of vertically reciprocatory type carriers, and accumulating means including two sets of vertical racks facing each other and connected to said type carriers, a plurality of totalizers located between the sets of racks, and means for moving said totalizers into and out of mesh with the racks. 85
10. A computing and recording machine having, in combination, a single set of reciprocatory type carriers, two sets of racks facing each other and attached to said type carriers, a plurality of sets of pinions located between said racks, and means for causing relative movement between the racks and the pinions to produce meshing and unmeshing of the racks and pinions. 90
11. In a computing machine, two parallel plates, two parallel shafts the ends of which are carried by said plates, a set of totalizer pinions on each shaft, said sets being out of mesh with each other, and means to support said plates for sliding movement whereby to move both shafts simultaneously. 115
12. A computing and recording machine having, in combination, a single set of reciprocatory type carriers, two sets of racks connected to said type carriers, two totalizers connected together for alternate operation only, means for simultaneously moving said totalizers to place one totalizer in mesh with one set of racks and to withdraw the other totalizer from engagement with the other set of racks, and carrying means in- 120
- 125

cluding two independent sets of transfer devices, one for each set of racks.

13. A computing and recording machine having, in combination, a set of reciproca-
5 tory type carriers and accumulating means including two sets of racks connected to said carriers, two totalizers each arranged

to mesh with a particular set of racks only, and means for simultaneously moving said totalizers to place one in mesh and to un- 10 mesh the other.

In testimony whereof, I have hereunto affixed my signature.

OSCAR J. SUNDSTRAND.
